COUPLING CAVITIES OF A MAGNETRON WITHOUT USE OF STRAPS

Ernest C. Okress, Elmira, N. Y., assignor to Westinghouse Electric Corporation, East Pittsburgh, Pa., a corporation of Pennsylvania

Application August 20, 1954, Serial No. 451,224

11 Claims. (Cl. 315—39.77)

My invention relates to magnetrons and in particular to a novel substitute for the straps which have heretofore been employed to stabilize the π mode of oscillation in multicavity resonant magnetrons.

A magnetron comprising a mere symmetric system of identical cavity resonators arranged in circular array about a cylindrical cathode can have

$\frac{N}{2}$

modes of electrical oscillation, where N is the number of cavities. Of these modes, that one in which alternate resonator segments are of opposite polarity, known as the π mode, is ordinarily desired for operation, and it has been wide practice in the art to provide straps which interconnect alternate segments with each other to provide adequate mode separation and give the π mode superior stability over other possible oscillation modes. However, the stabilization of the π mode thus attained proves insufficient with certain types of loading, and to increase stabilization, discontinuities (breaks) at points in the strapping at such angles to the cavity to which the power offtake (transducer) is attached as will increase the coupling to the transducer of competing oscillation modes has been resorted to.

Several serious disadvantages have, however, been found to result from use of straps, the most serious being a tendency to electrical breakdown between the straps and the resonator segments which they by-pass at separation-distances which are limited in magnitude by design factors. High electric gradient, bombardment by electrons emitted by the cathode and sublimation of electron-emissive material deposits on the straps and anode from the cathode surface all contribute to such breakdown tendencies.

In accordance with my present invention I eliminate strapping entirely and interconnect cavities of like phase by what are essentially waveguides at the periphery of the cylindrical anode structure.

One object of my invention is accordingly to provide an improved method of stabilizing the π mode of oscillation in magnetrons.

Another object is to provide a novel type of magnetron in which the π mode of oscillation is highly stabilized.

Another object is to provide a novel type of magnetron stabilized for the π mode of oscillation which is capable of operating with higher voltage gradients than stabilized magnetrons of the prior art.

Another object is to provide a magnetron of novel structure in which there is a wide frequency separation between the π mode of oscillation and competing modes.

Another object is to provide a novel method of destroying the symmetry of doublet fields of modes competing with the π mode of oscillation in a magnetron.

Still another object is to provide a novel method of altering the characteristic admittance of the resonant system in a cavity-type magnetron.

Other objects of my invention will become evident upon reading the following description and referring to the drawings in which:

Fig. 1 is a view, partly in section, of a twelve cavity magnetron embodying the principles of my invention;

Fig. 2 is a section along the lines II—II of Fig. 1; and

Fig. 3 is a detail section showing a modified form of my invention and taken along a similar plane to that of Fig. 1.

Referring in detail to Fig. 1, a magnetron embodying my invention may comprise a conventional cylindrical cathode 1, the peripheral active surface of which is indicated by a dotted circle, coaxial with an annular anode 2 having twelve equally spaced cylindrical cavity resonators 3 to 14 of similar dimensions. Each resonator is connected in usual fashion with the annular interaction space 15 surrounding cathode 1 by cavity interaction slot 16 having walls comprising parallel planes equally spaced from that axial plane of the cathode which includes the axis of the cylindrical cavity. Near the periphery of the anode are, at each end face, annular rectangular grooves 17 and 18 which are the principal portions of the cavity-interconnecting waveguides which I have previously referred to as constituting my present invention.

Each odd (or even) numbered cavity resonator is connected to the groove 17 by a passage 19 which may have a rectangular section; and each even (or odd) numbered cavity-resonator is connected to the groove 18 by a similar passage 21.

The periphery of the cylindrical anode 2 is enclosed by a wall of conventional type which has its ends closed in conventional fashion by end-walls (not shown). The cavity 3 has an outlet passage through wall 22 to which is connected in well-known fashion a waveguide 24 which may be of coaxial type and which forms a transducer for power outflow from the magnetron. Coupling of the transducer may be effected in a well-known way by a core-rod 25 extending through passage 23 and forming a loop 26 having its end connected to the wall of cavity 3.

It will be seen in Figures 1 and 2 that odd numbered cavity-resonators are all connected together by a waveguide comprising the groove 17 and the passages 19, while all even numbered cavity-resonators are connected together by a waveguide comprising the groove 18 and passages 21. This can be shown to result in altering the inductive coupling which exists between adjacent cavity-resonators and this changes the resonant frequency of the system.

It is possible to increase the insurance against any particular competing mode of oscillation interfering with the π mode by introducing a discontinuity 27 in the wave-transmission properties of the grooves 17 or 18, by decreasing or increasing its cross-section at a suitable distance K along it from the coupling loop 26 to destructively interfere with sustenance of the competing mode in question. The mutual coupling between cavities of like phase is dependent on the axial depth d and width m of the grooves 17 and 18, and the radial length l and width w of the passages 19 or 21. Generally speaking d may be of the order of the diameter of the cavities, and w and m be of the order of the width of the interaction slots 16. On the other hand the axial length l of passages 21 will in most cases be relatively smaller than w . The coupling guides between cavities of like phase are

non-resonant low impedance links, and no large electric gradients can develop in them.

It will be noted that the passages 19 or 21 are remote from the cathode 1 where deposits of material sublimed from the cathode and bombardment by electrons from the interaction space are negligible. The electric field in the resonator is likewise a minimum there. Hence little tendency to electric arc-over, such as that mentioned above as found in strapped magnetrons, exists in my arrangement. The structure likewise avoids the use of an asymmetrical resonator system such as those of "rising sun" type magnetrons and so eliminates the complexities of possible model operation which the duplex cavity-systems of the latter involve.

It may be pointed out that the existence of the transducer at one cavity resonator distorts the π mode pattern of all magnetrons, but that this distortion will be reduced by my present arrangement of waveguides interconnecting the cavities of like phase. There is also some π mode pattern distortion due to non-uniformity of the resonator slot field along the magnetron axis due to strapping at the ends of the cavities. This distortion is lessened where by present waveguide interconnection system is substituted for prior art strapping.

It is also possible to modify the structure shown in Fig. 1 by substituting ridged waveguides for the simple rectangular channels 17 and 18 to interconnect cavities of like phase. For a given load this system gives an increased stabilization if the ridged waveguide is proportioned to give the desired degree of coupling. Fig. 3 illustrates a ridged waveguide 30 substituted for the channel 17 in Fig. 1. The ridged waveguide is provided with a ridge member 32.

It may be pointed out that the arrangement here disclosed is very much simpler to make and operate than are the coaxial loop strapping systems of the prior art, and is also free of the spurious resonances likely to develop in strap systems because of their higher impedance and liability to resonance in their coupling.

It will also be noted that the coupling passages 19 or 21 need not be positioned exactly in line with the resonator slots 16, but may be off-set on one side or the other of that position to attain more complete screening from cathode electrons and sublimation deposits from the cathode.

I claim as my invention:

1. A magnetron comprising a cylindrical cathode and an anode comprising an annulus having an even number of cylindrical cavities with axes substantially parallel to the central axis of said annulus and arranged with their axes at points equally spaced on the circumference of a circle concentric with said annulus, a radial interaction slot connecting each said cavity with the inner surface of said annulus, an annular groove in each end face of each said annulus near the periphery thereof, a first passage from each odd numbered cavity only, said point passages connecting said each odd numbered cavity with one said groove and a second passage for each even numbered cavity only, said second passages connecting said each even numbered cavity with the other said groove.

2. A magnetron comprising a cylindrical cathode and an anode comprising an annulus having an even number of cylindrical cavities with axes substantially parallel to the central axis of said annulus and arranged with their axes at points equally spaced on the circumference of a circle concentric with said annulus, and a radial interaction slot connecting each said cavity with the inner surface of said annulus, an annular groove in an end face of said annulus near the periphery thereof, a passage for every other cavity only, said passage connecting said every other cavity with said annular groove.

3. An anode for a magnetron comprising an annulus having an even number of cylindrical cavities with axes substantially parallel to the central axis of said annulus

and arranged with their axes at points equally spaced on the circumference of a circle concentric with said annulus, a radial interaction slot connecting each said cavity with the inner face of said annulus, an annular groove in an end face of said annulus near the periphery thereof, and a passage for every other cavity only, said passages connecting said every other cavity with said groove.

4. An anode for a magnetron comprising an annulus having an even number of cylindrical cavities with axes substantially parallel to the central axis of said annulus and arranged with their axes at points equally spaced on the circumference of a circle concentric with said annulus, a radial interaction slot connecting each said cavity with the inner face of said annulus, an annular groove in each end face of said annulus near the periphery thereof, a first passage for each odd numbered cavity only, said first passages connecting said each odd numbered cavity with one said groove, and a second passage for each odd numbered cavity only, said second passages connecting said each even numbered cavity with the other said groove.

5. An anode for a magnetron comprising an annulus having an even number of cylindrical cavities with axes substantially parallel to the central axis of said annulus and arranged with their axes at points equally spaced on the circumference of a circle concentric with said annulus, a radial interaction slot connecting each said cavity with the inner face of said annulus, an annular groove in one end face of said annulus near the periphery thereof, a passage connecting every other cavity with said groove, and a section of altered cross-section at one point in said groove.

6. An anode for a magnetron comprising an annulus having an even number of cylindrical cavities with axes substantially parallel to the central axis of said annulus and arranged with their axes at points equally spaced on the circumference of a circle concentric with said annulus, a radial interaction slot connecting each said cavity with the inner face of said annulus, an annular groove in each end face of said annulus near the periphery thereof, a passage connecting each odd numbered cavity with one said groove, a passage connecting each even numbered cavity with the other said groove, and a section of altered cross-section in each said groove.

7. An anode for a magnetron comprising an annulus having an even number of cylindrical cavities with axes substantially parallel to the central axis of said annulus and arranged with their axes at points equally spaced on the circumference of a circle concentric with said annulus, a radial interaction slot connecting each said cavity with the inner face of said annulus, a ridged waveguide encircling the periphery of said annulus at one end face thereof and a passage connecting every other cavity with said ridged waveguide.

8. An anode for a magnetron comprising an annulus having an even number of cylindrical cavities with axes substantially parallel to the central axis of said annulus and arranged with their axes at points equally spaced on the circumference of a circle concentric with said annulus, a radial interaction slot connecting each said cavity with the inner face of said annulus, a ridged waveguide encircling the periphery of said annulus at each end face thereof, a passage connecting each odd numbered cavity with one said waveguide, and a passage connecting each even numbered cavity with the other said waveguide.

9. An anode for a magnetron comprising an annulus having an even number of cylindrical cavities with axes substantially parallel to the central axis of said annulus and arranged with their axes at points equally spaced on the circumference of a circle concentric with said annulus, a radial interaction slot connecting each said cavity with the inner face of said annulus, a ridged waveguide encircling the periphery of said annulus at one end face thereof, a passage connecting every other cavity with said ridged waveguide, and a section of altered cross-section at one point in said waveguide.

10. An anode for a magnetron comprising an annulus having an even number of cylindrical cavities with axes substantially parallel to the central axis of said annulus and arranged with their axes at points equally spaced on the circumference of a circle concentric with said annulus, a radial interaction slot connecting each said cavity with the inner face of said annulus, a ridged waveguide encircling the periphery of said annulus at each end face thereof, a passage connecting each odd numbered cavity with one said waveguide, a passage connecting each even numbered cavity with the other said waveguide, and a section of altered cross-section at one point in each said waveguide.

5. A magnetron comprising a central cathode surrounded by an anode, said anode comprising a plurality of segments projecting inwardly toward said cathode, said segments separated by cavity resonators, an annular groove in an end face of said anode near the periphery thereof and a passage for every other cavity resonator only, said passages connecting said every other cavity resonator with said groove.
